UNITED STATES PATENT OFFICE

WILLIAM R. HUTTINGER, OF PHILADELPHIA, PENNSYLVANIA

HIGH-VOLTAGE SWITCH

Application filed August 12, 1927. Serial No. 212,467.

My invention relates to switches, such, for example, as are set forth in my co-pending applications, Serial Nos. 722,281 and 689,256, filed June 25, 1924, and Jan. 29, 1924, respectively,—and it has for one object the provision of a high-voltage switch that shall be characterized by its ruggedness of construction, by its relatively light weight, and by its particular applicability to high-tension 10 lines, having voltages exceeding 220,000 volts.

Another object of my invention is to provide means, whereby such disalignment as occurs between a movable switch arm and a co-operating switch member may be eliminated during the closing operation. Such disalignment may be caused by the swaying of the switch arm under heavy wind loads, by the strain of the high-tension wire, by the settling 20 of the switch towers, and by other undesirable operating conditions.

Another object of my invention is to provide a high-tension switch, wherein the movable switch arm is locked to the co-acting switch member so long as the switch is closed and particularly while a movable contact portion of the switch arm is being actuated into engagement with the co-acting switch member. Such locking means is desirable in high-tension switches by reason of the relatively 30 large dimensions of the movable switch arm and the supporting insulator stacks. For example, the switch arm may be between ten and fourteen feet in length and the insulator stacks between five and eight feet in height. In such switches, while a relatively small force is required to cause the engagement of the movable contact portion and the co-acting switch member, this force, when multiplied 40 by the lever arm of the movable switch arm, is increased so as to cause large over-turning moments in the supporting insulator stack for said switch arm. The interlocking of the movable switch arm and the co-acting switch member during the closure operation renders negligible these over-turning moments and assures a rigid switch construction. Moreover, the locking of the switch parts while in their closed position tends to prevent the 50 opening of the switch due to the above-noted

undesirable load and operating conditions. Should separation of the switch parts occur under such circumstances, then not only would the switch be destroyed but the resulting surges on the high-tension line would cause 55 considerable damage to connected electrical apparatus.

A still further object of my invention is to provide such guiding and locking means for the relatively movable contact members of a high-tension switch, that the presence of ice and sleet does not interfere with the operation of the same. Such means is also designed to prevent the freezing together of the co-acting parts thereof when the switch is in its 60 closed position.

A still further object of my invention is to provide a switch comprising relatively movable contact members, an actuating insulator, and connecting means extending between said 70 actuating insulator and one of the contact members including worm-and-wheel mechanism, the actuating insulators being so positioned as to be subjected to tension when the switch is being opened.

Other objects and applications of my invention, as well as details of construction and operation, whereby my invention may be practiced, will be apparent more fully hereinafter, when taken in connection with the 75 accompanying drawings, wherein

Figs. 1 and 2 are side elevational and top plan views, respectively, of a high-tension switch embodying my invention;

Fig. 3 is an enlarged detail longitudinal sectional view of the co-operating contact portions and their housings, the sectional plane being taken on the line 3—3 of Fig. 4;

Fig. 4 is a horizontal sectional view taken on the line 4—4 of Fig. 3; and

Fig. 5 is a detail vertical sectional view of the interlocking housing portions, the sectional plane being taken on the line 5—5 of Fig. 3.

Referring to the drawing, a horizontally 95 positioned beam 1, which may be supported on the top of a transmission line tower (not shown), provides a rigid support for spaced, parallel stacks of insulators 2 and 3. A supporting bracket 4 is mounted on the upper 100

end of the vertical insulator stack 2 and it is provided with a substantially horizontal supporting surface 5. A stationary contact member or element 6, for purposes of illustration, has been shown as comprising a standard portion 7 and an inclined downwardly extending bifurcated end portion 8 forming spaced, spring contact blades 9 and 11.

10 The portions 7 and 8 of the stationary contact member 6 may be protected from sleet and snow by means of a housing 12 which is mounted on the surface 5 of the supporting bracket 4. The housing 12 is provided with 15 openings 13 and 14, the opening 13 being disposed in a side 15 facing the insulator stack 3 and the opening 14 being in a base portion 16. A stationary contact member 17 extends through an opening 18 in a side 19 of the housing 12, co-operating with a movable element 21 of a disconnecting switch 22. The portion of the stationary contact member 17 projecting beyond the housing 12 may be protected by a hood 23. The stationary contact 25 member 7 is also connected to a flange 24 affording a mounting for a terminal connection 25 of usual design.

The spring contact blades 9 and 11 of the stationary switch 6 are adapted to co-act with 20 a movable contact portion 26 of a switch blade or arm 27, a main body portion 28 of which is mounted to move in a vertical plane on a pivot pin 29 carried by a bracket 31 positioned on the upper end of the upright insulator stack 3, as will appear hereinafter in greater detail.

The main body portion 28 of the switch arm 27 preferably comprises longitudinally extending tubular members 32, 33 and 34 which 25 are disposed in the form of a triangle converging at one end in a common member 35 carrying a housing 36 for the movable contact portion 26. At the other end of the triangular construction, spaced lugs 37 and 38 30 respectively are provided which are secured to the tubular members 32 and 33. These lugs are perforated to receive the pivot pin 29. The tubular member 34 is secured to a strap member 39 which is provided with a central 35 opening or slot 41 extending between spaced abutments or shoulders 42 and 43, for reasons as will presently appear. The strap member 39 and the lugs 37 may comprise one single casting. A terminal connection of usual design is provided for the movable switch arm 27.

In accordance with my invention, the housing 36, which is mounted on one end of the main body portion 28, is provided with a 40 pivot pin 45 having bearings 46 and 47 disposed in the upper portion of the side walls thereof. The pivot pin 45 has rigidly secured thereto the movable contact portion 26 of the switch arm 27. The electrical connection between the pivoted contact portion 26 and the

main body portion 28 may be made more perfect by means of a flexible cable 48 extending from a hub portion 49 of the movable contact portion 26 to a cable support 51 on the main body portion 28. The lower portion of the housing 36 is removed to provide an opening 52 through which the pivoted contact portion 26 may pass as it is actuated into engagement with the spring blades 9 and 11 of the stationary contact member 6. Figs. 70 1, 3 and 4 illustrate in solid-line the movable contact portion 26 in its extended position wherein the switch 1 is closed, while Fig. 1 shows in dot-and-dash line the retarded position in which the pivoted portion 26 is 75 contained within its protective housing 36 and the switch is open.

In the practical construction and operation of my high-voltage switch, considerable difficulty was had in closing the same by reason of the disalignment of the switch arm 27 and the stationary contact member 6. The disalignment is caused by the swaying of the switch arm which may be, say, twelve feet in length, under heavy wind loads; by reason of unbalanced strains in connected high-tension wires; or by the settling of the switch towers (not shown). This difficulty is overcome in my invention by the provision of an abutment 53 that extends upwardly from an upper side 54 of the housing 12, said abutment terminating in a rounded end portion 55 which co-acts with a flange portion 56 of conical form mounted on an upper outer edge 57 of the housing 36. The flange portion 56 comprising an angled side wall portion 58 and a curved base portion 59 adapted to receive the complementary end portion 55 of the abutment 53, as illustrated in Figs. 3 and 5.

When the switch is being closed, should the pivoted contact portion 26 of the switch blade 27 be out of alignment with the co-acting spring blades 9 and 11, the movement of the abutment end portion 55 over the wall portion 58 of the conical flange 56 causes the disalignment to decrease, being finally reduced to zero when the end portion 55 seats in the socket or base portion 59 of the flange 56. Thus the outer free end of the switch blade 27 is supported by the mounting of one protective housing on the other. The portion 60 of the housing 12 which includes the abutment 53, is so depressed that the rounded end portion 55 does not extend substantially above the remaining portion of the upper side 54 of the housing 12. Such disposition assures that the upper end 55 of the abutment 53 is well within or below the flux field. Since the overhanging flange portion 56 surrounds the abutment 53, danger of these co-acting parts freezing together is very greatly eliminated.

It is also noted that the co-acting portions 53 and 56 of the housings 12 and 36 serve in 125

addition as interlocking portions which are effective not only when the contact portion 26 is being actuated into engagement with the spring-contact fingers 9 and 11 but also thereafter. While a relatively small force is required to actuate the movable contact portion 26, this force when multiplied by the lever arm of the switch blade 28 represents a large over-turning moment which if not properly balanced in a short time would cause the destruction of the switch 1. One advantage, therefore, of causing the upper ends of the insulator stacks 2 and 3 to be interlocked while the contact portion 26 is being actuated is that the large over-turning moments thus developed in the insulator stacks are counterbalanced. Another advantage of causing the upper ends of the insulator stacks 2 and 3 to be tied together so long as the switch 1 is closed is that it very greatly decreases the danger of the separation of the switch members 6 and 27 due to the settling of the switch towers (not shown) and the like. Should such separation occur, the resulting surges on the high-tension line connected to the switch terminals 25 and 44 would cause considerable damage to connected electrical apparatus and the probable destruction of the switch 1.

My invention further contemplates the actuation of the main body portion 28 and the relatively movable contact portion 26 of the switch blade 27 by means of a third upright insulator stack 61 which may be mounted on the beam 1 in the same plane as the insulator stacks 2 and 3 and parallel thereto. The position of the insulator stack 61 is such that the stationary insulator stack 3 is situated between the actuating insulator stack 61 and the remaining stationary insulator stack 2. Such relative arrangement of parts permits the insulator stack 61 to be subjected to tension strains, while opening the switch 1, as will presently appear in greater detail.

A lower end of the actuating insulator stack 61 may be mounted on an anti-friction thrust bearing 62 carried by the supporting beam 1, and it is provided with a shaft which extends through the beam 1 and terminates in a bevel gear-wheel 63. The bevel gear-wheel 63 meshes with a bevel gear wheel 64 mounted on a shaft 65 extending to adjacent units (not shown), and it is operated by a bevel gear-wheel 66 carried by a main operating shaft 67. The upper end of the actuating insulator stack 61 is provided with a vertically extending shaft portion 68 journaled in an anti-friction bearing 69 carried by arms 71 and 72 constituting integral extensions of the bracket 31.

In view of the large dimensions of the insulator stack 61, I have provided a special connecting means 73 between the actuating insulator 65 61 and the switch arm 27, so that

the tortional strain in the insulator stack 61 may at no time reach a dangerous value with ordinary accumulations of ice or snow present. To this end, the insulator stack 61 is operatively associated with the main body portion 28 and the pivoted contact portion 26 of the switch blade 27 by mechanism which is so designed that said switch parts move only a relatively small amount in response to a large movement of the actuating insulator stack 61. That is to say, the mechanism or means 73 is designed so that the mechanical advantage of the actuating insulator stack 61 is very large. One such form of mechanism is illustrated in the drawing as screw-gearing.

This so-called screw-jack connection 73 between the insulator stack 61 and the switch arm 27 involves the use of a worm 74, which is mounted on the upper end of the shaft 68, 85 and a worm-wheel 75 which has been illustrated as a quadrant pivotally mounted on the portion of the pivot pin 29 intermediate the bracket lugs 37 and 38. The quadrant 75 may comprise a toothed portion 76, a hub 90 portion 77 and interconnecting arms 78, 79 and 81, the latter arm extending through the opening 41 in the strap member 39 so as to be movable between the shoulders 42 and 43. The portion of the quadrant 75 adjacent to 95 the connection between the arm 81 and the toothed portion 76 is provided with a pivot pin 82 for a link 83 which extends to a link 84 mounted on an outer end portion 85 of the pivot pin 45.

The dimensions of the slot 41 are such that the pivoted contact portion 26 may be actuated clear of the co-operating spring contact fingers 9 and 11 into the protective housing 36 prior to the engagement of the quadrant arm 81 with the end abutment 42. It is also noted that the point of engagement of the abutment 42 on the arm 81 is spaced from the pivot pin 29 sufficient to afford the desired leverage on the movable switch arm 27.

As shown in the drawing, the worm 74 has a relatively flat pitch, so that the worm-and-wheel 73 may be non-reversing under the action of the switch blade 27. This non-reversing or non-overhauling characteristic is particularly important, since the switch blade 27 is locked in any desired elevated position, regardless of whether or not power is applied to the actuating insulating stack 61.

When the switch 1 is in the closed position shown in solid-line in the drawing, the pivoted contact portion 26 is in engagement with the stationary contact element 6 and the switch-arm housing 36 is supported on the stationary housing 12, the co-acting portions 125 55 and 56 establishing an interlocking connection therebetween. Also, the quadrant arm 81 is positioned intermediate the abutments 42 and 43. If the insulator 61 is now turned, the quadrant 75 and arm 81 thereof 130

are moved, causing the pivoted contact portion 26 to be actuated out of engagement with the stationary contact member 6 into its protective housing 36. When this movement has been completed, the quadrant arm 81 is in engagement with the end abutment 42. The continued movement of the quadrant 75 now causes the pivoted contact portion 26, as well as the main body portion 28, to be moved in a 10 vertical plane about the pin 29 as a pivot. Such movement may be continued until the switch blade 27 has been actuated a desired distance from the stationary contact member 6, one such position being shown in dot-and-dash lines in Fig. 2. It is noted that during this opening movement, the insulator stack 61 is subjected to tension strains inasmuch as the effect of the worm 74 is to pull the switch arm 27 about the pivot pin 29. 15 Hence, the load on the thrust bearing 62 is reduced to a minimum when the switch is being opened.

When it is desired to close the switch 1, the direction of rotation of the insulator stack 25 61 is reversed, whereupon the movable switch arm 27, by reason of its weight, follows the upwardly moving quadrant arm 81. Should there be a tendency for the switch arm 27 to remain in its raised position, the arm 81 is 30 merely actuated into engagement with the shoulder or abutment 43, forcibly actuating said switch arm 27 downwardly. Experience has shown that once the switch arm 27 has started to move downwardly, the weight 35 thereof is sufficient to cause the same to follow the upwardly moving quadrant arm 81.

The lowering of the switch arm 27 is continued until the housing 36 rests on the housing 12, any disalignment occurring between 40 the switch arm 27 and the switch member 6 being eliminated during the final portion of the downward movement by the engagement of the abutment 53 with the conical flange 56. When these co-acting portions finally seat, as 45 shown in Figs. 3 and 5, not only the switch arm 27 and the stationary contact member 6 are rigidly interlocked but also the adjacent upper ends of the insulator stacks 2 and 3.

The continued movement of the actuating 50 insulator 61 following the interlocking of the housings 12 and 36 causes the arm 81 to be actuated clear of the shoulder 42, permitting the quadrant 75 to move independently of the switch arm 27. During this movement, by reason of the linkage 83 and 84, the pivoted contact portion 26 is actuated from its protective housing 36 through the opening 52 thereof and also through the openings 13 and 55 14 of the housing 12 into engagement with the spring-contact blades 9 and 11 of the stationary contact member 6, thereby completing the final closing operation of the switch. At this moment, the operation of the insulator stack 61 is automatically discontinued in 60 65

the usual manner. When the switch 1 is to be again opened, the foregoing procedure is repeated.

While I have shown only one embodiment of my invention, for the purpose of describing the same and illustrating its principles of construction and operation, it is apparent that various changes and modifications may be made therein, without departing from the spirit of my invention, and I desire, therefore, that only such limitations shall be imposed thereon, as are indicated in the appended claims or as are demanded by the prior art.

I claim:

1. A switch comprising relatively movable switch members, one of said switch members being provided with a housing portion, a housing for the other switch member, means for establishing an interlocking relation between said housing and housing portion when said switch members are in predetermined positions, and an actuating insulator subjected to tension strains when said switch is being opened.

2. A movable contact member provided with a housing, a cooperating contact member provided with a housing, said housings being so disposed that one engages the other when said switch members occupy desired relative positions, the engaging portions of said housings, interlocking, and means for raising said first-mentioned housing, said means including an actuating insulator subject to tension strains due to said housing movement.

3. The combination with a movable switch member provided with a housing, of a co-operating switch member also provided with a housing positioned to engage said first mentioned housing when said switch members occupy predetermined positions, the engaging portions of said housings constituting guiding and interlocking means, and means for separating said housings including an actuating insulator provided with a bearing, the load on said bearing being a minimum upon a separating movement of the housings.

4. A switch comprising relatively movable contact members, of which one is provided with a housing and a contact portion movable in said housing, a housing for the other contact member, and actuating means for at least one of said contact members including worm-and-wheel mechanism, and an actuating insulator provided with a bearing, whereby said switch may be closed, said housings having co-acting portions constituting guiding means, the load on said bearing being a minimum upon the opening of said switch.

5. A switch comprising a pair of relatively movable contact members, of which one is provided with a housing and a portion movable in said housing, a housing for the other

contact member, said housings having co-operating portions constituting guiding means when the switch is being closed, at least one of said co-operating portions being disposed within the flux field, and an actuating insulator subject to tension loads when said switch is being opened.

6. A switch comprising relatively movable switch members, one member being provided with a movable contact portion, housings for one of said switch members and said movable contact portion, respectively, said housings having co-acting portions constituting guiding means, means for actuating at least one of said switch members including self-locking gearing, and an insulator, said insulator having a bearing subject to minimum loads when said switch is being opened.

7. A switch comprising relatively movable switch members, one member being provided with a movable contact portion, housings for one of said switch members and said movable contact portion, respectively, means carried by at least one of said housings adapted to serve as guiding means for at least one of said switch members, and means for actuating at least one of said switch members including screw gearing, and an actuating insulator, said actuating means permitting a predetermined lost-motion, said insulator being provided with a bearing subject to minimum loads when said switch is being opened.

8. A switch comprising relatively movable switch members, of which one is provided with a movable contact portion, supporting insulator stacks for said switch members, respectively, housings for one of said switch members and said movable contact portion, respectively, screw-jack means for actuating at least one of said switch members, said housings having co-operating portions constituting guiding means, said co-operating portions being so formed that one serves as a protective hood, and an actuating insulator for said screw-jack means positioned on the side of one of said insulator stacks opposite to the adjacent sides of said insulator stacks.

9. A switch comprising a plurality of insulators, relatively movable switch elements, means for actuating one of said switch elements comprising a worm-and-wheel, said worm being mounted on one insulator and said wheel being mounted on another insulator, and means for establishing an interlocking relation between said switch elements, the insulator supporting said worm being subjected to tension loads when said switch is being opened.

WILLIAM R. HUTTINGER.
